ITEM AND TOTAL PRINTING MECHANISM
FOR CALCULATING MACHINESRobert Léon Gourdon, Paris, France, assignor to
Societe Anonyme dite: Centre d'Etudes M. B. A.,
Paris, FranceApplication October 3, 1950, Serial No. 188,224
In France October 8, 1949

6 Claims. (Cl. 235—60.37)

1

This invention relates to registering and totalizing devices, of the types adapted—or not—to print or otherwise record the amounts registered or totalized therein, for use in calculators, cash-registers, and similar accounting and/or business machines.

In machines of the class to which the invention is directed, numbers or amounts to be registered are first made up or entered by means of a keyboard or similar means, and selector wheels or drums are then brought into action to define the amplitude of the subsequent rotation of each of the digit-carrying cylinders or drums provided in the machine, and from which the amounts or items are then transferred to counters, dials and/or recording or printing means.

It is the main object of this invention to provide a device adapted for use in a machine of the type just defined, for registering a series of partial amounts or items, and simultaneously and automatically totalizing the registered partial amounts in full, the values of the successive digital orders (e. g. hundredths, tenths units, tens, hundreds, etc.) being simultaneously registered in a single operation.

The amounts or items thus registered and totalized may be recorded as by printing, or entered into a counter, or both.

My invention essentially provides a registering and totalizing device of the type described, which comprises two sets of coaxial toothed wheels each carrying upon its respective teeth digits from zero to nine, one set of wheels being controlled by the rotation of the digit-carrying cylinders of the calculating or other machine, while the second set of wheels is controlled by the first set of wheels through the medium of a carry-over mechanism.

In addition to the essential characteristic just described, a device according to the invention may further include one or more of the following features:

(1) Each of the character-carrying toothed wheels of the first set (hereinafter termed "partial item" wheels) is secured on a tubular shaft coaxial and rotatable with a digit-carrying cylinder, all the tubular shafts being interfitted in one another.

(2) Each character-carrying toothed wheel of the second set (hereinafter termed "total" wheels) is disposed adjacent to the partial item wheel pertaining to the same digital order as it, and is slightly smaller in diameter than said related partial item wheel adjacent to it.

(3) Each of the partial item wheels has its zero character carried on a spring-biassed eccen-

2

trically-mounted ring, so as to be at all times urged radially inwardly of the wheel to a position depressed or retracted relatively to the remaining characters of said wheel, and latching means provided to counteract the spring action and keep the zero character on a common cylindrical enveloping surface with said remaining character of the wheel;

(4) The carry-over mechanism comprises a movable structure for each of the digital orders provided, said movable structure comprising a reciprocating carry-over conditioning member and a set of two integral gear pinions each with as many gear teeth as the aforementioned character wheels, and an oscillating frame common to all of said movable structures and adapted to effect the carry-over operations, said frame having the respective sets of pinions mounted for free rotation on it, the arrangement of said mechanism being such that:

(a) The first of the two integral pinions in each set is rotated by the partial item wheel of the corresponding digital order, while the second pinion of the set drives in its rotation the total wheel of the same digital order.

(b) As the first of the integral pair of pinions in each set reaches an angular position corresponding to an angular rotation of the corresponding partial item wheel equalling nine-tenths of a revolution from the origin (or zero) mark, it releases a spring element of the reciprocating member of the structure relating to the next higher digital order, said element then being interposed into the path of the reciprocating member of the movable structure relating to the next lower digital order.

(c) As the first of the integral pair of pinions in each set moves from its angular position corresponding to a rotation of the related partial amount wheel equalling nine-tenths of a revolution from the origin (or zero) mark to the angular position corresponding to an additional angular rotation equalling one-tenth of said wheel, it causes a displacement of the reciprocating member relating to the next higher order in one direction, said member being maintained in its displaced position and displacing in turn in the same direction the reciprocating member of the movable structure relating to the further next higher order, if the spring-element of the last-mentioned structure had already been interposed in the path of the reciprocating member of the structure corresponding to the next lower order, as previously described.

(d) On actuation of the oscillatory frame carry-

ing the sets of integral pinions, the frame disengages the first of each set of pinions of those structures in which the reciprocating member was previously shifted as above from the partial amount wheel which was rotating said pinion until that point, and it causes engagement of a gear-toothed portion of the thus-shifted reciprocating member with the second pinion of the set, in order to rotate said second pinion by the amount of one additional tooth (i.e. one-tenth of a revolution, this amount corresponding to the carry-over to be effected), this rotation being fully transmitted to the related total wheel.

(5) The reciprocating member is in the form of a sliding plate or strip formed over part of its periphery with a partially toothed cut-out adapted, upon the strip being shifted in either of the two ways indicated above, to rotate by the amount of one tooth the second pinion of the related set which was previously brought into engagement with said toothed portion by the actuation of the oscillatory frame common to all the movable structures.

(6) The cut-out mentioned in (5) is formed in its periphery with a shoulder against which a boss integral with the oscillatory frame is adapted to engage upon actuation of the frame, so as to maintain the related strip in its shifted condition throughout the period of engagement of its toothed portion with the pinion.

(7) The reciprocating strip is provided with a spring-loaded latch normally retained in idle condition but adapted, upon the strip being shifted either way, to block the strip in its shifted position.

(8) A re-set or clearing mechanism is provided for restoring the total wheels to their initial positions after the sum total of a desired plurality of previously-registered partial items has been registered by the device, said re-set mechanism comprising, for each of the digital orders considered, a pickup member adapted to be engaged by a projecting element of the first of the integral pairs of pinions of each set when driven by friction (in a direction reverse from its normal rotation) by the effect of a rotation imparted to the shaft on which said sets of pinions are freely mounted, and said projection being retained in engagement against said pick-up member, causing a relative slippage of the related pair of pinions about its shaft until all of the sets of pinions thereon have been brought in a similar manner to a position in which their projections are all in engagement with said pick-up members; in this position, all of the total wheels have been restored to their initial angular positions, while still being each positively connected with the second pinion of the respectively related set of pinions.

(9) A further set of toothed wheels is provided in addition to the partial item and total wheels, each wheel of said further set each carrying a reference mark or index on each of its teeth, and said further wheels being controlled from index-carrying cylinders or drums rather than from digit-carrying drums as were the first two sets of wheels.

(10) Sets of so-called "check-strip printing" wheels are further provided each carrying characters on each of its teeth for printing on a checking-strip. The check-print wheels are adapted to be rotated by the partial item wheels upon actuation of a suitable control means to disengage the driving connection leading from the partial item wheel to the drive connection

5 leading to the carry-over mechanism, whereupon said partial item wheels can no longer actuate the first pinions of the carry-over mechanism structures.

10 (11) The partial item wheels are further adapted, upon disengagement of the drive-connections as mentioned in (10), to operate through a suitable transmission preferably including a special clutch unit to be described, a device for registering the amounts or numbers into a "credit" counter.

(12) A latching mechanism is provided for blocking the partial item, total item, and contingently the check-strip printing wheels, and place into suitable alignment those of the character-bearing teeth of the various wheels which are to make a printing impression.

(13) The said latching mechanism comprises a pair of spring-latches adapted to block simultaneously, under the effect of an appropriate control, either the total and partial item wheels together with the check-strip printing wheels, or separately and selectively at the requisite instants, the total wheels on the one hand, and the partial item and check-strip printing wheels on the other.

(14) Blocking of the total wheels alone may be effected by a special control operating in synchronism with the action exerted on the aforementioned control member for disconnecting the power transmission path leading from the partial item wheel, from the power-transmission path leading to the carry-over mechanism, thereby enabling direct printing on a checking strip to be accomplished.

(15) Blocking of the partial item and check-strip printing wheels, and blocking of the total wheels, is effected by means of one or more sets of pivotal rollers displaceable in one direction to block successively all of said wheels one after another, and adapted on further displacement in the said direction, to block only the partial item and check-strip printing wheels, and displaceable in the opposite direction to block only the total wheels.

(16) A connection is provided between the carryover reset mechanism and the above-mentioned latching mechanism to synchronize the unlatching of the total amount wheels with the re-set operation.

(17) The same latch member which serves to block all of the partial item wheels also serves to restore the zero character on each of the partial item wheels to its position upon the enveloping cylindrical surface of the other characters of the wheel.

(18) The partial item and total wheels, contingently also the check-strip printing wheels, are arranged to be capable of performing a printing operation by the application of one or more suitable strips or sheets of paper against a generatrix of the enveloping cylindrical surface of said wheels.

(19) Where the total wheels are in alternating relationship with the coaxial partial item wheels, as previously described, they are normally preventing from producing an impression since the diameter of the former is smaller than that of the latter; however, the retraction of the zero-characters on the partial item wheels under the effect of an unlatching of these wheels after said zeros have been aligned along the printing generatrix of the enveloping surface of said wheels, will then allow the total wheels to perform their printing operations alone.

(20) The strip(s) or sheet(s) of printing paper is (are) mounted on a pivotally mounted printing block adapted to apply it (them) against said printing generatrix of the partial item and total wheels and contingently the check-printing wheels, and comprising a movable inking device adapted preliminarily to coat with ink the characters or reference marks carried by those teeth of said wheels that are aligned with the printing generatrix.

(21) The printing strip or sheet is fed over the printing block past the printing wheels by a feed device adapted to feed the strip by a variable amount in response to a variable amplitude control actuated by an appropriate control member.

(22) The variable amplitude control comprises a cam-sector having a toothed edge portion driven by the printing block and formed with a notch adapted to engage with a projection on a pivoted lever thereby imparting to said lever an angular rotation of controlled amplitude.

(23) Means are provided for cutting off the printing strip or sheet after printing. Said means may comprise a knife member adapted to be forced back into a slot formed in a platen disposed over said strip by a control mechanism actuated by a suitable control member.

(24) The knife-carrier member of the cutting device may also be made to carry plates adapted, upon actuation of the cutting mechanism, to firmly apply the strip to be cut off against one or more pads carrying date or other information to be printed.

(25) Means are provided for ejecting the strip portion thus printed and cut off. Such means may comprise a drive roller adapted to rotate a gear pinion, and released for instance by the cut-off control mechanism when the latter is operating.

(26) Operation of the ejector means in addition to being synchronized with the operation of the cutting means, may further be synchronized with the operation of the inking means, which is then adapted to cock the ejector means, and said inking means being further synchronizable with the printing block lifting movement.

(27) All or part of the above-mentioned mechanisms and means may be controlled in timed relationship with one another from one or more camshafts carrying appropriate cams adapted to assure with accuracy the requisite sequence of steps, at the accurate instants at which each should start, and be completed.

The above and further objects and features of the invention will appear from the ensuing detailed description of one specific form of embodiment of a register and totalizer according to the invention, including means for printing the amounts registered and/or totalized. In the accompanying drawings:

Fig. 1 is a perspective view of the assembly including the digit-carrying and the index-carrying cylinders, the printing wheels, the carryover mechanism, the general counter- and sales counter-actuating levers, the power-transmission from the partial item printing wheels to the carryover mechanism, and the transmission from the carryover mechanism to the total printing wheels.

Fig. 2 is a similar view on an enlarged scale but showing exclusively the parts relating to a single digital order; however, as concerns the shafts of the various mechanisms, the shafts for all the digital orders have been shown.

slightly forward of one of the movable strips of the carryover mechanism; in particular this figure shows a part of the credit counter-actuating mechanism, omitted in the foregoing figures.

Fig. 4 is a section on a plane extending intermediate two adjacent printing wheels, and showing inter alia the blocking means for said wheels.

Fig. 5 is an axial section on a diametric plane of the common shaft of the digit-carrying and reference-carrying cylinders and the printing wheels.

Fig. 6 is an elevation of the carryover mechanism.

Fig. 7 is a perspective view, with parts broken away and omitted for greater clarity, of two adjacent carryover mechanism assemblies relating to adjacent digital orders.

Fig. 8 is a similar view of the carry-over mechanism as a whole and some related parts, said mechanism being shown in its idle condition as resulting from the successive entry of a number of partial items.

Fig. 9 is a similar view corresponding to Fig. 8 but showing the carryover pinions rotated by an amount not greater than the angular extent of one tooth.

Fig. 10 is a view similar to Fig. 8 but corresponding to the position of the mechanism at the end of the entry of a new amount into the carry-over mechanism.

Fig. 11 is a view similar to Figs. 8 to 10, but further illustrating the frame of the carryover mechanism and the manner in which it operates during the carryover operation proper.

Fig. 12 is a similar view showing further the re-set mechanism.

Fig. 13 illustrates the drive of the carryover mechanism frame.

Fig. 14 shows the drive of the re-set mechanism.

Fig. 15 is a perspective view of the printing block.

Fig. 16 is a section of the block on the vertical plane XVI—XVI of Fig. 15, and shows in particular the means for printing the heading of a price-slip.

Fig. 17 is a section of the printing block on vertical plane XVII—XVII of Fig. 15 and shows in particular the feed mechanism for the price-slip at the beginning of the feed movement.

Fig. 18 is a similar view but relates to the end of the feed period.

Fig. 19 is a section of the printing block on line XIX—XIX of Fig. 15 and shows in particular the means controlling the feed of the printing block proper and the means controlling the feed of the inking roll.

Fig. 20 is a perspective view of the printing wheel blocking mechanism with some associated parts, and

Fig. 21 is a timing chart for the operation of the device.

Taken as a whole, a calculating machine or a cash-register of the type to be described as embodying the features of the invention, comprises a tabulating system selectively controlled from a keyboard or the like, a general driving system for imparting the requisite displacements to the various parts which are to be moved during a registering operation, various counters and transmission mechanism, in addition to the particular mechanisms to be described with greater detail as forming the peculiar subject matter of the present invention.

For a more detailed description of the other features of the machines, reference may be had

for example to my French Patents Nos. 953,768, 953,769, and 953,770 of May 30, 1949, No. 936,159 of February 16, 1948, and No. 937,324 of March 8, 1948, all relating to a machine to which the present invention may be advantageously applied.

Among the means subjected to the action of the tabulating mechanism and the general driving system of the machine are the digit-carrying and reference-carrying cylinders, from which the amounts to be registered are transferred into the counters, dials and/or printing mechanism.

In Fig. 1 of the accompanying drawings five digit-carrying cylinders are shown, numbered 1 to 5, which may be assumed as respectively corresponding to the tenths, units, tens, hundreds and thousands digital orders. Next come two reference-carrying cylinders 6 and 7 respectively bearing accessory information, such as information adapted to identify the nature of the transaction and the responsible salesman.

The digit-carrying cylinder 1 (see Fig. 5) is secured on a tubular shaft 9 surrounding an innermost shaft 8 and surrounded in turn by the successive tubular shafts 10, 11, 12, 13, 14 and 15 rotatable independently from one another. Each of the tubular shafts is rotatable with a digit-carrying or a reference-carrying cylinder. Thus the cylinder 2 is secured on shaft 10, cylinder 3 on shaft 11, and so on, cylinder 7 being secured on shaft 15. An outermost tubular shaft 16 surrounds the whole assembly of shafts 10 to 15 and serves as a support for freely-rotatable gear wheels 31 to be described presently. The digit-carrying or reference-carrying cylinders 1 to 7 are all assembled in a group at the right-hand end of the nest of tubular shafts. Mounted on the left-hand end of shaft 8 are seven toothed wheels serving to print items or numbers of the checking strip. These check-strip printer wheels are numbered 17 to 23. The tubular shafts 9 to 15 extend to points somewhat short of the wheels 17 to 23 and their ends are stepped as shown in Fig. 5. Keyed on the projecting end of shaft 9 is a wheel 24 for printing the tenths (and contingently hundredths) of partial items. Adjacent the wheel 24 is a wheel 30 for printing the tenths (and contingently hundredths) of a total amount. The wheel 30 is freely rotatable on shaft 9 so that rotation of the tenths digit-carrying cylinder 1 will rotate only the wheel 24. Similarly, secured on the projecting ends of each of the remaining tubular shafts 10, 11, 12 and 13 are wheels 25, 26, 27 and 28 for printing the respective digital orders of the partial items corresponding to each of the said remaining tubular shafts. And adjacent to each of the wheels 25, 26, 27 and 28 and freely rotatable about the end of each of the shafts carrying said wheels, are freely-rotatable wheels 31, 32, 33 and 34 which perform functions similar to that of the wheel 30 and which likewise handle the total amounts.

Mounted for free rotation on the tubular shaft 13 and adjacent the free wheel 34 is a second free wheel 35 the sole function of which is to print on the slip handed to the purchaser adjacent to the printed totals (e. g. to print as a total the ten-thousands digit obtained by the carry-over operation).

The wheels 24 to 28 comprise the "partial item" wheels, and the wheels 30 to 35 are the "total" wheels.

With the reference-carrying cylinders 6 and 7 respectively correspond wheels 29 and 36 secured on the tubular shafts 14 and 15. The operation of these "reference" wheels is substantially the

same as that of the partial and total amount wheels, except that they do not involve any carry-over operations.

It will be observed that the wheels 24, 25, 26, 27, 28, 29 and 36, each secured on its individual tubular shaft, are slightly greater in diameter than the wheels 30, 31, 32, 33, 34 and 35, each rotatable on its tubular shaft. This peculiarity will be referred to in greater detail later on.

It is further noted that the wheels 25 and 31 of the units order are somewhat longer than the others, on account of the decimal point between the units and tenths orders. The same applies to the thousands wheels 28 and 34 because of the comma between the thousands and hundreds.

Grouped about the assembly 37 including the shafts 8 to 16 are the various co-operating mechanisms participating in the printing and carry-over operations and more generally in the registering of the tabulated amounts. The general arrangement of these mechanisms in relation to the assembly 37 will now be briefly described.

Shown at 38 (Fig. 1) is the transmission which assures printing of the amounts on the checking strip. At 39 is the transmission from the partial item wheels to the carry-over mechanism, the latter shown at 40. The mechanism 40 drives the total wheels through a transmission 41. Between the latter and transmission 39 and above the printing wheels is located a printing-wheel blocking mechanism (not shown in Fig. 1) shown on an enlarged scale in Fig. 4.

Below the carry-over mechanism 40 are L-levers 42 which transmit the amounts being registered to the general counter and the sales counters. Below the printing wheels is the printing block 151 (Fig. 15). To the rear of and below the transmission 41 and the carry-over mechanism 40 lies part of the general driving system of the machine. And above and slightly forward of transmission 39 is a mechanical connection including pinions 64 and 70 (Fig. 3) and leading to the credit counter, for automatically printing the sales made on credit.

Each of the mechanisms referred to above will now be described in fuller detail. The printing wheels 17 to 23, which are the check-strip printer wheels, each comprise a number of equal teeth some of which, regularly spaced from one another, carry the successive printing type characters from 0 to 9, as shown in Fig. 2 in the case of the printing wheel 17.

The partial item wheels 24-28 and total wheels 30-34 have their periphery divided, as shown in the case of total wheel 34 in Fig. 4, into ten equal sectors each marked by a tooth bearing one of the characters from zero to nine. These characters of course follow one another in the natural digital order.

Only on the partial item wheels, the zero character designated by the reference 43 is not carried by the wheel itself, but by a ring 44 surrounding the tubular shaft (e. g. shaft 13) upon which the particular partial amount wheel considered, 28 in the instance described, is mounted.

The ring 44 is internally eccentric as shown at 45 in Fig. 4, so as to be movable along the direction of that diameter which extends through the zero digit. At the opposite end of this diameter there is a lug 46 cut out from the material of ring 44 and bent at right angles to the plane of the ring, said lug projecting into a notch 47 formed in the wheel 38 under consideration. To each side of the lug 46 two bosses 48, 49 are

formed on the periphery of the ring 44. When the ring 44 is so disposed that its diameter extending through the digit zero (called "zero-diameter") is vertical, a latch member 233 (Fig. 4) located above the printing wheels becomes capable of moving down in between the teeth of said wheels, and of forcing the rings such as 44 downwards so that the zero digits of the latter (which at such time are disposed on a common lowermost generatrix) will all assume a position in which they lie upon the enveloping cylindrical surface of the partial amount wheels. If the latch member is not actuated, a spring 50 housed in a recess in the wheel 28 under consideration, pushes back the lug 46 outwards and thus urges the zero digit of the corresponding wheel towards its hollow shaft (e. g. 13).

As already said, the total wheels have a diameter slightly less than the partial item wheels. Normally such an arrangement would appear to preclude the total wheels from printing, since as described presently, the printing operation is accomplished through a lifting movement of the printing block which applies the strip of slips and the checking strik to be printed, up against the lowermost generatrix of the enveloping cylindrical surface of the printing wheels. However, assuming that the zero digits of the partial item wheels are all aligned on a common lowermost generatrix, and that the blocking mechanism is not forcing the rings 44 downwards, then the zero digits of the partial item wheels, urged upwards, as stated above, by the springs 50, are in a retracted condition. This allows the printing block to contact the digits of the total wheels aligned on a common lowermost generatrix of their cylindrical envelope.

Referring to Fig. 2, the end of the tubular shaft corresponding to the tenths (contingently hundredths) order can be seen at 9, the partial item wheel at 24 and the total wheel relating to the tenths (contingently hundredths) order at 30. The wheel 24 meshes with a gear 51 secured on a hollow shaft 52 carrying at its opposite end a gear pinion 53. Fitted around the tubular shaft 52 are further tubular shafts corresponding to the remaining orders of digits, and the whole nest 54 of which is carried on an innermost solid shaft 55 extending from end to end of the nest 54. Pivot on the shaft 55 is a lever 51 carrying at its opposite end a so-called "number" key 53 adapted to permit the printing of a number which should figure in the total to be registered, corresponding for instance to an identification number of the article sold. It will be understood that there corresponds to each of the tubular shafts of the nest 54 an individual gear wheel 51 and an individual pinion 53, as shown in Fig. 1. The pinion 53 drives a mechanism for the registering of items on a checking strip carried by the printing block. For this purpose, a gear 59 carried by a tubular shaft 60 meshes with the pinion 53, while a gear 61 rigid with the other end of the tubular shaft 60 meshes with the checking strip printing wheel 17 corresponding to the order of magnitude under consideration, herein tenths (and contingently hundredths). The tubular shaft 60 is carried by a solid shaft 62; further tubular shafts surrounding the shaft 60 each carry an individual gear wheel 61 and an individual pinion 59 corresponding to another order of magnitude, said tubular shafts together forming a nest or assembly designated 63. The assembly of pinions 53, tubular shafts 60 and pinions 61 constitute the previously mentioned transmission 38 (Fig. 1).

The pinion 53 of the order of magnitude under consideration also meshes with a pinion 79 rotating on a shaft 65 for registering, when required, an item on the credit counter. Rotating on a shaft 66 (see Fig. 3) carried by a frame 67 is a lever 68 carrying a pin 69 on which a pinion 70 is mounted. The lever 68 may rock as indicated by the arrow 71 to bring the pinion 70 into engagement with the pinion 64. The frame 67 carries, for each order of magnitude, a positioning pawl 73 through the action of which the teeth of the gear 70 are made to assume a correct position relatively to the teeth of the pinion 64, when the lever 68 rocks in the direction indicated by arrow 71. Moreover the periphery of lever 68 is formed with a cam 74 cooperating with a cam lever 75 held in position by a two-armed spring 76 resting in a bracket 77 of the frame 67. A special "credit" key (not illustrated, but understood to be secured on shaft 66), is adapted to cause the lever 68 to rock in the direction indicated by arrow 71 to bring pinions 70 and 64 into engagement. The tabulated items are entered in the credit counter (not illustrated) by depression of the credit key, over the mechanical transmission chain consisting of the pinions 53, 64 and 70 corresponding to the different orders of magnitude involved in the operation. If the credit key is not depressed, the credit counter remains out of the mechanical circuit.

Secured on the lever 57 of number key 58 is a lever 78 provided with a bent extension forming a kind of cage within which there are pivoted as many pinions 79 as there are numerical orders under consideration. The pinions 79 each mesh with one of the pinions 53; they are mounted on as many interfitting tubular shafts. The pinions 79 are further in mesh each with a transmission gear 81 freely rotatable on the outermost tubular shaft 16 of the shaft assembly 37. The gears 81 serve to transfer the tabulated item into the carry-over mechanism.

The assembly including rocking cage 78 with its pinions 79 and gears 81 forms what was previously designated (in connection with Fig. 1) the transmission 39.

If the number key 58 is depressed in direction of arrow 80 (Fig. 3); the assembly including levers 57-78 with the pinions 79 is bodily swung about the shaft 55, raising the pinions 79 which are thus disengaged from the gears 81.

The above is what occurs in the case where a credit item is registered, and the partial item wheels then directly transmit the information of the tabulated amount to the credit counter through the medium of the sets of pinions 51-53-64 and 70.

If on the other hand the number key 58 is not depressed, the lever 78 remains in its normal position and each of the pinions 79 of the various numerical orders meshes with one of the gears 81, which then transmit the tabulated amount to the carry-over mechanism and then, through the transmission 41 to be described later, to the total gears.

The carry-over mechanism will now be described with more particular reference to Fig. 7. The said mechanism comprises three main elements: carry-over repairing strips 82 (equal in number to the orders of magnitude for which the machine is designed), pinion assemblies 112, 113, 114 to be more specifically described later, and lastly a swinging frame 102, 121, 122 (Fig. 6) which executes the carry-over operation proper;

11

moreover, a reset or clearing device 132, 135, 136 (Fig. 12) is provided.

With each order of magnitude there corresponds a vertical strip 82 carried at its upper end by a rod 83 and at its lower end by a rod 84. Both rods are horizontal and are common to all the strips 82 of the carry-over mechanism. Each of the strips is recessed at its upper end at 85 and presents on either side of the rod 83 two straight edge portions 86 and 87 engaging in a groove 88 provided in the periphery of the rod. The recess 85 extends above and below the rod 83 (mainly below). The lower part of the strip 82 is further recessed at 89 and two edges 90 and 91 similar to the edges 86 and 87 engage into a groove 92 in the rod 84. The recess 89 extends mainly above the rod 94.

From the arrangement just described it follows that each of the strips 82 can slide vertically on the rods 83 and 84, such sliding movement being effected from an idle position in which the strips 82 are shown in Fig. 7.

Moreover, each strip 82 is formed towards its rear with a cutout 93 the upper edge of which is provided with a toothed sector 84. This cut-out merges with the base of the strip 82 over a shoulder 95.

Under the cut-out 93 each strip 82 carries a pin 96 about which is freely pivoted a latch strip 97 having a concave edge 98. The end 99 of a spring 100 urges the strip 97 upwards, but a stop boss 101 carried by a bar 102 (Fig. 11) blocks the latch strip 97. The spring 100 passes around and takes support on the lower rod 84. It is blocked at 103 in lugs cut out and bent back from the base of the strip 82. The other arm 104 of the spring 100 urges forward a lever 105 pivoted about a pin 106 supported by the strip 82. The lower end of the lever 105 has a tongue 107 folded at right angles to the strip 82, while the upper end comprises a hooked nose 108 which is adapted to engage with a stop lug 109 carried by the strip 82. The tongue 107 is directed towards the strip 82 of the order of magnitude next below that corresponding to the strip 82 under consideration. The latter strip further comprises a tongue 110 perpendicular to its plane and directed towards the next order of magnitude.

Extending through the cutouts 93 in the strips 82 is a longitudinal spindle 111 carrying, adjacent each strip, a toothed pinion 112. The latter is mounted rotatably on the spindle 111 and is integral with a bushing 113 also rotatably mounted on spindle 111 and rigid with a pinion 114. The assembly of pinions 112 and 114 and the intermediate bushing 113 forms, for each strip 82 and consequently for each order of magnitude, a movable structure independent, in its rotation, from the movable structures of the other orders of magnitude. Each pinion 112 is engaged (see Fig. 3) by the gear wheel 81 of the order of magnitude under consideration. The pinion 114 of the same order engages a gear wheel 115 mounted on a shaft assembly 116 parallel with the spindle 111 and consisting of several hollow shafts 117 interfitted into one another and supported internally by a shaft 118 as in the case of the other shaft assemblages already encountered so far. Each recessed shaft corresponds to one order of magnitude and rigidly connects the pinion 115 of the order of magnitude under consideration with (Fig. 2) a gear wheel 119 forming part of the assembly 41 (Fig. 1) and meshing with the total printing wheel 30 of the order of magnitude under consideration.

12

The oscillating frame of the carry-over mechanism consists of two end flanges 121 and 122 interconnected (Figs. 6 and 11) by the bar 102 which carries the stop bosses 101, and which is suitably assembled to the end flanges, for instance by an assembly flange 123 screwed with two screws 124 and 125 to the corresponding end flange 122 (Fig. 11). The oscillating frame described carries, between its end flanges 121 and 122, the spindle 111 of the bushings 113 of gears 112 and 114.

It will be observed (Figs. 11 and 12) that the end flange 122 carries at its lower part a gear sector 126 adapted to impart an oscillatory movement to the oscillating frame about the shaft assembly 116. The latter of course extends at 127 and 128 (Fig. 11) through the end flanges 122 and 121. The construction of the shaft assembly 116 is especially visible in Fig. 11, where it is clearly seen that each of its hollow shafts 117 is rotatable exclusively with one of the pinions 115.

The drive mechanism for the oscillatory frame of the carry-over mechanism will be described after the resetting mechanism.

This mechanism (see Fig. 12) consists of a gear pinion 129 rigid with the shaft 111 and adapted to be drivingly engaged in the direction of the arrow 130 in Fig. 12, by a gear sector 131 formed on a lever 132 rotatable about the shaft assembly 37 and carrying about its hub 133 a second gear sector 134 allowing the reset mechanism to be driven from a mechanism to be described later. The reset mechanism further comprises a bar 135 parallel to the shaft 111 and provided with pick-up hooks 136 equal in number to that of the orders of magnitude for which the machine is designed. Each hook 136 consists of a generally flat strip curved at its end opposite from the bar 135. Each of the pinions 112 of the shaft 111 carries a stud 137 eccentric relatively to the shaft 111 and adapted to cooperate with one of the pick-up hooks 136. Each hook 136 is associated with a particular pinion 112 and corresponds to a given order of magnitude.

The drive mechanism for the frame of the carry-over mechanism is illustrated in Fig. 13, which is a section of the machine perpendicularly to the shafts or sets of shafts 37, 111, 116. The gear sector 126, of the end flange 122 and the assembly 116 about which the frame can oscillate are visible in this figure. The end flange 122 comprises an arcuate guide slot 140 co-operating with a fixed spindle 141. Keyed on a camshaft 142 belonging to the general control mechanism of the machine and driven by the crank or the motor ensuring the registering operation proper, is a sector-cam 143 partially toothed, whose teeth mesh with the sector 126 at the time of the carry-over operation proper and execute the operation when a carry-over is effectively to be performed.

The drive device of the reset mechanism is illustrated in Fig. 14. Keyed on the camshaft 142 is a further cam 144 with which is associated a follower roller 145 carried by a lever 146 pivoted about a fixed shaft 147 and engaging by means of a set of teeth 148 the teeth 149 of a partially toothed sector 150 engaging with the teeth 134 of the lever 132 carrying the sector 131.

The cam 144 is obviously displaced angularly relatively to the sector-cam 143, in order that the reset operation should occur at the desired time after the carry-over operation proper. In the

part of this description describing the operation of the machine, the sequence in which the cams of shaft 142 operate will be indicated with reference to the timing diagram of Fig. 21.

I shall now describe as a whole the printing block which takes care simultaneously of the printing of partial items, totals and numbers (e. g. reference numerals) on a check strip (which remains in the machine until entirely printed or until it is periodically removed) and on a strip forming tickets or slips which are separated and ejected automatically following each registering operation.

The printing assembly (Fig. 15) comprises the printing blocks 151 proper and shaft 152 on which a reel 153 is mounted on which is wound a strip 154 adapted to provide the slips.

Rotatable on a shaft 155 is a reel 156 on which is wound a check strip 157 which, after having passed over a roller 158, passes in between two rollers 159 and 160, then over two rollers 161 and 162 before it passes around the top of, and is applied against, a bar 163 arranged along the lowermost generatrix of the gears 17 to 23 providing for the printing of the check strip. The check strip is then driven by a drive cylinder 164, passes in between the roller 160 and a roller 165 and is then directed by two rollers 166 and 167 towards a roller 168 on which it is automatically wound so as to remain permanently taut.

The slip-strip 154 is engaged (Fig. 16) in between a plate 169 of the printing block and a guide 170. These two elements define a channel 171 which terminates at 172 where the slip cut off from the check strip is ejected outwards.

I shall now describe the drive mechanism for the printing block proper, the slip feeding means and a mechanism which simultaneously drives and cuts off, for ejection, the slip strip and marks said strip with certain given indications such as date, and name of the firm using the machine.

The printing block 151 comprises two side flanges 173 and 174 (Figs. 15 and 16) carrying the plate 169 mentioned above. The upper edges of the flanges 173 and 174 are conformed to the path which is to be followed by the slip strip to bring the part of the latter which is to be utilised under the lowermost generatrix of the gears 24 to 36. Within the block 151 is a mechanism designed to assure printing. The printing operation is carried out by a raising of the block 151 about the shaft 175 as a result of which the part of the strip 154 to be printed upon (extending in alignment with the bar 163) and accordingly the part of the strip 157 located on the bar 163 is brought into contact with the lowermost generatrix of the cylinder formed by gears 17 and 23 and gears 24 to 36. After the printing has been completed, a reverse rotation restores the block 151 to its initial position.

The mechanism which is responsible for this movement (see Fig. 19) consists of a cam 176 keyed on the camshaft 142 extending through the printing block. The cam 176 acts on a roller 177 carried by a shaft 178 rigidly secured to and acting as a spacer for the flanges 173 and 174. The manner in which the movement is produced will easily be understood from Fig. 19. The upper part 179 of plate 170 is recessed to allow the slip-strip to contact the lowermost generatrix 180 of the cylinder made up of the partial item and total printing wheels and the check-strip printing wheels. Two shafts 181 and 182 rotatably mounted between the two flanges of block 151

carry drive rollers adapted to feed the paper by mechanism to be described later. Fig. 15 shows the two drive rollers 183 and 184 mounted on shaft 182.

Movable between these two shafts 181 and 182 is an inking roller 185 carried by arms 186 and applied in its idle position against an inking pad 187.

The arms 186 are freely rotatable about a shaft 188 interconnecting the flanges 173 and 174. Each of these arms carries a gear sector 189 which, after the inking cylinder 185 has reached the right-hand end part of its stroke, comes into mesh with a gear pinion 190 (Fig. 19) keyed on a shaft 191 controlling the slip-ejecting mechanism, the slip then being cut off as described later. The arms 186 are urged back to their idle position by a torsion spring 192 wound about the shaft 188. The drive for the inking cylinder 185 is provided for by a lever 193 keyed on the camshaft 142 and carrying a first roller 194 adapted to engage a projection 195 of the lever 186 and a second roller 196 adapted to engage another projection 197 of lever 186. The first pair of rollers 194—195 controls the first part of the inking cylinder stroke, the second part being controlled by the second pair of rollers 196—197; the return stroke is assured by the torsion spring 192.

The inking cylinder during its displacement passes under the teeth of printing wheels lying on the generatrix 180 and deposits ink on the characters carried by said teeth. However, if the teeth carrying the zero characters of the partial items wheels are raised owing to the de-actuation of the latching mechanism (not yet described) ink may then be deposited on the total wheels, a result which would not be possible if the zeros of the partial account wheels were retracted or if characters of said wheels other than zeros appeared along the generatrix 180.

The shafts 181 and 182 carry at least at one end thereof, a gear pinion 198 and 199 (Figs. 17 and 18). Each of these pinions meshes with one of the sets of teeth 200 or 201 of a sector 202 freely rotatable about shaft 188 secured to flanges 173 and 174. Sector 202 is provided at its base with a cam surface composed of a projection 203 and a shoulder 204 between which is formed a cutout 205 into which is engageable the nose 206 of a lever 207 pivoted about the shaft 175 and carrying a rotatable roller 209 on a pin 208, said roller being adapted to be initially engaged either in the rear narrower portion 210 or in the wider front portion 211 of a cutout formed in a part 212 adapted to be actuated from a special key (called "addition key," not illustrated).

In normal idle position, when the key is not depressed, the roller 209 is engaged in the narrow end portion of the cutout in the part 212 (Fig. 18). If however the addition key is depressed, the part 212 is rocked backwards (Fig. 17) and the roller 209 is then engaged in the widened entrance portion of the cutout in part 212.

In the first case (key idle), when the printing block 151 returns from its raised position (shown in Fig. 18) to its idle position, the projection 203 of part 202 (moved with block 151) is brought to bear against the nose 206 of lever 207 which can only pivot about shaft 175 by an angle corresponding to the clearance of roller 209 within the narrow portion 210 of the cutout of part 212. And, under these conditions, the part 202 or its gear sectors 200 and 201 can only be rotated about the shaft 188 by a corresponding small amount;

the gear pinions 198 and 199 and with them the drive rollers 183—184 driven in turn, then only feed the slip-strip by the amount of one line space (Fig. 18).

In the second case (key depressed, Fig. 17) when the printing block 151 returns to its idle position (shown in Fig. 17) the projection 203 can, by bearing against the nose 206, cause lever 207 to rock by an angle corresponding to the clearance of roller 209 within the widened aperture of the cutout in part 212; this causes a larger-amplitude rotation (corresponding to this angular displacement of lever 207) of the part 202 (and consequently of the sectors 200 and 201) about the shaft 188; and consequently a longer feed of the slip-strip, equal in this case to five line spaces for example (Fig. 17).

Pivoted about shaft 188 is a crank 213 (Fig. 16) carrying on its lower end a roller 214 engaging in a notch 216 of a part 215 movable from the position shown in chain lines at 217 in Fig. 16 to the full line position of the same figure. The crank lever 213 comprises at its upper end a cam-notch 218 into which is engaged and in which is movable a roller 219 carried by a rod 220 having a forked lower end so as to present a notch 221 engaging the shaft 188 upon which the part 220 takes support. Its position is, moreover, determined by the contact prevailing between the roller 219 and the notch 218. The part 220 is movable upwards, being guided on the one hand by the shaft 188 in notch 221 and on the other hand by the roller 219 and notch 218, which cause this movement.

At its upper end the part 220 comprises a knife 222 and plates 223 and 224 which, as a result of the raising of part 220, are applied beneath the slip-strip and strongly push the latter against a pad 225 upon which permanent data are engraved, such as the name and address of the firm using the machine. This pad is placed along one of the generatrices of the cylinder swept by the inking roller 185 and is supplied with ink as this roller passes along it.

A date-maker (not visible in the drawing) may further be provided, the useful generatrix of which is also disposed along a generatrix of the cylinder swept by the inking roller 185 and slightly displaced angularly relatively to the pad 225. The lever 213 is adapted, during its displacement, to act with the upper edge 226 of its notch 218 upon a cam 227 rigid with a pawl 228 pivoted on a fixed pin 229 and associated with a ratched wheel 230 keyed on the shaft 191 controlling the slip-ejecting mechanism; this mechanism may consist for example of a drive cylinder rigid with the shaft 191 which as shown in Fig. 16, lies underneath the shaft 182.

The operation of the ejecting device is in this case as follows: the lever 213, moved by the part 216, releases the ratchet wheel 230 from pawl 228 and, when the gear sector 189 (Fig. 19) engages the pinion 190, a rotation of the drive shaft 191 causes the slip, printed and cut off by cutter 222, to advance and consequently be ejected. The cutter acts by applying the slip-strip against a platen 231 placed above the slip-strip and formed with a slot 232 into which the cutter 222 engages at the end of the cutting operation.

As previously noted, the printing wheels are of three kinds; wheels for printing partial items on the check-strip and, for the slip-strip, the partial item wheels and total wheels. These three categories of wheels may be blocked either

5

10

15

16

simultaneously or independently by means of latching mechanism now to be described.

Essentially, the wheels are permanently latched to preserve the alignment of the printing characters carried by the teeth of said wheels.

The latching mechanism comprises three kinds of elements: the latches proper, the rollers actuating said latches, and the means for actuating said rollers (Fig. 20). The latches consist of a part 233 comprising forks 234 (also see Fig. 4) directed downwards and adapted to engage in straddling relationship with the uppermost tooth of a total wheel. Corresponding with each total wheel there is a fork 234. The part 233 possesses at its top a flange 235 disposed above a fixed plate 236; a spring-plate 237 interposed between this plate and the flange 235 tends to retain the part 233 in raised, that is in unlatched position. The second latch is formed by a part 238 generally similar to 233, that is its upper end having a flange 239 which is applied through a spring-plate 240 against a fixed plate 241.

At its lower end the part 238 comprises, towards the right, forks 242 (Fig. 20) similar to the forks 234; each of the forks 242 straddles the upper tooth of a partial amount wheel. The forks 242 alternate with the forks 234 in the same way as the partial item wheels alternate with the total wheels. The part 238 furthermore comprises, towards the left, a secondary latch 243 (Figs. 19 and 20) comprising a bevel and adapted to engage between two consecutive teeth of the wheels responsible for the printing of the partial accounts on the checking strip. This secondary latch 243 simultaneously acts on all of the wheels 17 to 23.

Keyed on a shaft 244 are two brackets 245 and 246 carrying rollers 247, 248 or 249 (not visible) and 250. The rollers 248 and 250 engage between the two parts 233 and 238 and maintain both these parts depressed simultaneously, thus ensuring a general latching of all the printing wheels. The rollers 247 and 249 on the other hand act on the part 238 only and block the partial item wheels and check-strip printing wheels. On the other hand, a frame 251 having arms 252, 253, 254 freely pivoted on the shaft 244, carries at the end of its arms 252 and 253 rollers 255 and 256 adapted to latch the total wheels through the medium of the part 233. The frame 251 carries at the end of its arm 254 a roller 257 engaging in a notch 258 of a hub 259 rotatable about the set of shafts 54. This hub is rigid with a spacer 260 connected with the lever 78 and forming therewith the sort of cage already mentioned before and within which the pinions 79 are rotatable. It will be observed moreover that the lever 78 presents at its lower end a cutout 261 into which engages a roller 262 carried by a part 263. If the numeral key 58 is depressed, the spacer 260 is rocked and consequently, through the medium of hub 259, the rollers 255 and 256 are depressed; the part 233 then blocks the total wheels. The remaining rollers 247 to 250 are controlled by rotation of the shaft 244. This shaft comprises a gear pinion 264 in mesh with a sector 265 rigid with a lever 266 having a nose 267 cooperating with the nose 268 of a cam 269 carried by a shaft 270 located roughly above the carry-over mechanism and adjacent to the digit-carrying cylinders. This shaft 270 forms part of and is driven by the general control mechanism of the machine for the same reason as the camshaft 142.

It is necessary on the other hand to provide for

75

a connection between the carryover mechanism reset mechanism and the latching system to synchronise the unlatching of the total wheels with the re-setting operation. For this purpose, the lever 132 (Fig. 20) comprises a projection 271 and a ramp 272, said projection cooperating with a pawl 273 mounted in a stirrup 274 carrying a roller 275 adapted to ride over the ramp 272. A spring 276 tends to apply the pawl 273 against a lever 277 pivoted at 278 in the stirrup 274. The lever 277 acts by its nose 279 on a pin 280 on a small lever 281 keyed on the shaft 244.

The operation of the device described in its structural details will now be disclosed.

In such operation, three types of operations are to be assumed separately:

(1) The registering of a number, that is, a set of digits which are to figure on the slip-strip and on the check-strip without interfering with the other numbers the sum total of which it is desired to obtain.

(2) The registering of a partial item or "sub-total," that is to say a number which is to be subsequently added to other numbers of similar type, already registered; it is necessary in this hypothesis to bring the carry-over mechanism into play, but on the other hand, the total wheels should not exert their printing action.

(3) The registering of a total resulting from the addition of several partial items as defined in (2).

The three above instances will be successively considered, after first however having described the operation of the carry-over mechanism.

It will first be observed that the pinions 112 each have ten teeth opposite to one of which a stud 137 is secured. For greater convenience, the angular position of these pinions will hereinafter be indicated by referring to the corresponding tooth of a similar pinion assumed to be stationary and the stud of which is assumed to be located in its initial position, that is in the position for which the digit already registered in the corresponding order of magnitude is zero. The pinion 112A of Fig. 8 is in a position corresponding to that of the reference pinion considered. The possible positions of each of the studs 137 are the positions 0 to IX.

If the total already registered is say the number 6,983.90, then the position of the various pinions 112 is initially as follows:

The pinion 112F corresponding to the tenths order (and contingently the hundredths) has its stud 137F in position IX. Position IX is a special position about which more will be said later.

The stud 137E of pinion 112E is in position III which does not offer any peculiarity. In the same way, the stud 137D of pinion 112D is in position VIII which has nothing special about it either. On the other hand, stud 137C of pinion 112C is in position IX, a particular position. The position VI occupied by stud 137B of pinion 112B has nothing in particular. On the other hand, the position 0 of stud 137A has this peculiarity that it is the next position following that at which carry-over operations are first effected (position IX).

The position IX occupied by stud 137F has this peculiarity that said stud bears against the stop-lug 109E on the strip 82E, but it does not cooperate with a lever 105, for such a lever is not provided for the lowermost order of magnitude. In IX position, the stud 137C also comes into contact with lug 109B; but moreover, it rocks the lever 105B in the clockwise direction, looking at the

carry-over mechanism from its left-hand end in Fig. 8. This lever 105B thus pushed back brings its tongue 107B beneath the tongue 110C of the next lower order of magnitude (hundreds). The remaining levers 105 are in such positions that their noses 108 engage the stops 109.

By way of example, it will now be assumed in order to illustrate the manner of operation of the carryover mechanism that, after having registered partial items, the sum total of which amounts to 6,983.90 it is desired to register and totalize a new partial item amounting to 3,021.10.

As is known this item is formed on the keyboard of the machine and, by means of tabulating mechanism forming no part of this invention elements are brought into play which cause rotation of each of the digit carrying cylinders by angular amounts proportional to the digit of corresponding order of magnitude.

In the example just selected, the angular values corresponding to the rotation of the digit-carrying cylinders 1 to 5 will respectively be as follows:

25	Tenths-----	$\frac{1}{10}$ of a revolution
	Units-----	$\frac{1}{10}$ of a revolution
	Tens-----	$\frac{1}{10}$ of a revolution
	Hundreds-----	Zero rotation
	Thousands-----	$\frac{1}{10}$ of a revolution

30 When the accounting is commenced by starting the general control mechanism of the machine and rotating the registering handle (where the registering operation is effected manually), the above-indicated rotations are effected automatically and simultaneously and cause, through the pinions 51—53—79 and 81, equal rotations of the pinions 112, and, through the medium of the bushing 113, pinions 114 and 115 and pinions 119, equal rotations of the total wheels, but, for greater clearness, the new item to be commenced is going to be split up in order to provide a clear understanding of the behaviour of the carry-over mechanism.

Accordingly we shall first only consider the 45 initial tenth of a revolution of the digit-carrying cylinders, which corresponds to a rotation by one tenth of a revolution of the pinions 112. This rotation corresponds to the starting of a fractionated item equal to 01, 011.10; each of the 50 pinions 112 rotates by one tenth of a revolution except pinions 112A and 112C of the ten-thousands and hundreds.

55 As a result of this tenth-of-a-revolution, the stud 137F applies against the stop 109E and lowers the strip 82E which slides vertically along the rods 83 and 84. The latching strip 97E moves down, disengaging the boss 101E, at the same time as the strip 82E compresses the spring 100E which, since the boss 101E remains stationary in space, takes advantage of the fact that the latter is clear of the latching strip 97E to rotate this latching strip counterclockwise and bring the concave edge 98E of said strip into engagement with the boss 101E as the strip 82E moves up again, after the stud 137F has cleared the stop 109E; the strip 82E is then blocked in an intermediate position lower than its initial position and the carry-over is prepared (Fig. 9).

70 At the end of this first tenth-of-a-revolution, the stud 137F which occupied position IX (see above), has moved to position 0; the pinion 112E has moved from position III to IV; stud 137D from position VIII to position IX (in which it is ready to produce a carry-over); pinion 112B has passed from position VI to position VII,

19

pinion 112A has not moved, neither has pinion 112C.

The number registered by all the pinions 112 then is 07,994.00 instead of 06,983.90.

The second rotation by one tenth of a revolution is equivalent to transferring into the carry-over mechanism an amount corresponding to 01,010.00. As the result of this second tenth of a revolution, the pinion 112F has not shifted its position, no more has pinion 112E; but pinion 112D, which until then stood in position IX has acted by its stud 137D on stop 109C of strip 82C and caused a depression of the latter similar to the depression of strip 82E during the first tenth of a revolution. The latching strip 97C has then moved from its position in Figs. 8 and 9 to its position in Fig. 10. In moving down to assume (like the strip 82E previously) an intermediate position, the strip 82C has pressed with its tongue 110C on the tongue 107B of the lever 105B previously pushed back from strip 82B. This last-mentioned strip has thus in turn been moved downwards and has also assumed an intermediate position in which it is retained by its latch 97B actuated by the spring 100B. The pinion 112C has not revolved, but pinion 112B has effected a second tenth of a revolution which has brought it from position VII to position VIII. The pinion 112A has again remained stationary. It will, moreover, only be rotated at the time of the effective transfer on the carry-over from one pinion to the other. Already at this time, two fresh carry-over operations are prepared owing to the intermediate position assumed by the strips 82C and 82B (Fig. 10).

As the result of the second tenth of a revolution, the amount entered in the carry-over mechanism becomes 08,904.00.

During the third tenth of a revolution, the pinions 112C to 112F inclusive do not revolve, and only pinion 112B moves from position VIII to position IX, which is equivalent to entering an amount equal to 01,000.00. As the result of this third tenth of a revolution, the amount registered by the carry-over mechanism pinions is the amount 09,904.00.

The carry-over operations are then ready to be carried out, and the strips 82 are in the positions indicated in Fig. 10, where only the strips 82A and 82D have remained in their initial position. It will be observed that, owing to the lowering of the strips 82B and 82C, the tongues 107A, 107B are now engaged under the tongues 110B and 110C of these strips.

The situation, in brief, before the ensuing carry-over registering operation, is the following:

The digit-carrying cylinders have transmitted to the total-wheels for the tenths, units, tens, hundreds and thousands (which respectively registered the figures 9, 3, 8, 9 and 5) rotations respectively equivalent to $\frac{1}{10}$, $\frac{1}{10}$, $\frac{1}{10}$ of a revolution, zero, and $\frac{1}{10}$ of a revolution; accordingly said total wheels are now registering the figures 0, 4, 0, 9 and 9. The ten-thousands total wheel is still standing at zero. And the strips 82 for the units, hundreds and thousands are lowered and ready to allow registering of the carry-over results thus prepared, so that the total wheels for the units, hundreds and thousands should finally register the respective figures 5, 0, 0 and the ten thousands wheel should register the digit 1. The total wheels will then be registering the amount 10005.00 (sum total of the second item 3,021.10 with the first item: 6,983.90).

This operation consisting of registering the

20

prepared carry-over amounts is accomplished as follows:

The cam-sector 143 (see Fig. 13) supported on the camshaft 142 and meshing with the teeth 126 of the flange 122 of the carry-over oscillating frame, causes a displacement of the latter about the shaft assembly 116 in the direction of arrow f in Figs. 13 and 11.

Two cases are then to be considered:

(1) That in which the strips 82A to 82E have not been depressed;

(2) That in which the three strips 82B, 82C, 82E have been depressed on preparation of the carry-over and which were maintained in their intermediate positions by the latching strips 97.

In the first instance, the pinions 114 moved with the motion of the frame, come out freely from the cutout 93 of the related strip without encountering any resistance. They cease meshing with the related gears 81; they lose all positive activity, this being explained by the fact that they have no carry-over to register.

In the second case on the other hand, the pinions 114 in rocking forward encounter the gear sectors 94 carried by those of the strips 82 which have been depressed to their intermediate position; and the frame's oscillatory movement causes, on contact of said gear sectors 94 with which they are in mesh, a rotation of said pinions 114 equal in amount to one tooth, i. e. tenth of a revolution.

Returning to the previously considered example, that is where the partial item 3,021.10 was registered following a total equalling 5,983.90, the pinion 112E rigid with pinion 114E meshing with gear sector 94E will rotate by one tenth of a turn; it will therefore move from position IV to position V and, through the medium of pinion 115E (which the pinion 114E, still in meshing engagement, will rotate by one tenth of a turn) and of the related pinion 119, the units total wheel will register the figure 5.

Transfer of the carry-over from the tenths order will thus have been accomplished.

In the same way, engagement of pinion 114C with sector 94C of strip 82C will shift pinion 112C from position II to position 0, and the digit registered by the hundreds total wheel will be zero. The tens digit will have been unaltered, since there is no carry-over transfer to be effected from the units order to the tens order.

However, the digit registered by the thousands order total wheel will in the same way pass from 9 to 0. Lastly the pinion 114A, which so far had not been brought into action, will move by one tenth of a turn because of the action of the gear sector 94B of the strip 82B on pinion 114B and the registering of the carry-over of the thousands order to the ten-thousands order. The ten-thousands total wheel will thus register the figure 1; and the amount finally registered by the total wheels through the medium of the carry-over mechanism will then be 10,005.00.

It is to be observed that engagement of each of the pinions 114E, 114C and 114B with the gear sector 94 of the corresponding (lowered) strip 82 has been made possible owing to the fact that the pivotal rotation of the oscillating frame 121, 122 carries the bar 102 with it; the boss 101 of this bar, corresponding to each of said three strips will during such pivotal movement, pass over the shoulder 95 of its strip and consequently maintain the latter depressed throughout the engagement of the pinion 114 with the gear sector 94. Before the end of the

pivotal movement of the oscillating frame, the total wheels are re-set, if this operation is called for. At the end of the pivotal movement of the oscillating frame and during the movement of the latter back again to its initial position, the bosses 101 carried in the movement of said frame, pass below the shoulders 95 of the three depressed strips 82E, 82C and 82B and, in passing under these shoulders, rock the latch strips 97E, 97C and 97B in a direction reverse from that of their initial rocking movement; at the same time the corresponding springs 100 cause the three strips 82 under consideration to move up again, and the entire carry-over mechanism is restored to its initial position.

A fresh partial account can then be added to the provisional total thus registered. For this purpose, one may proceed again as just described, but it is also possible, for instance if it is desired, to recommence an addition or if one has finished totalizing previously registered partial items to erase the accounts registered by the total wheels through the use of the re-set device operation of which will now be described. The cam 144 of shaft 142 (Fig. 14) is then brought into play to effect such re-setting. Acting on the roller 145, it rotates the lever 146 about the fixed shaft 147 and the teeth 148 of the lever 146 meshing with that of sector 150, causes rotation of the lever 132 (Fig. 12) which then moves in the direction of the arrow 130; the gear sector 131 of this lever 132 then engages with the pinion 129 which causes a reverse rotation of pinions 112. This is because the shaft 111 carrying them is driven by pinion 129 and drives by friction the bushings 113 until the studs 137 of pinions 112 have been brought against the pick-up hooks 136 carried by the pick-up bar 135. As soon as a stud comes into contact with its pick-up hook, the related bushing 113 slips over the shaft 111 (without such slippage reacting at all on the adjacent pinions), while the remaining pinions 112 successively bring their studs 137 against the related pick-up hooks.

The developed extent of the teeth of the gear sector 131 corresponds to a maximum value of nine teeth; this gear sector can therefore bring back to "0" position any pinion 112 which was located at the "IX" position.

It will be noticed that, under such conditions, the rotation of each of the pinions 112 is equal to the value of the angle which that pinion has to cover in order to restore its stud 137 to zero, regardless of the angle by which the latter should move.

In the reverse movement of rotation of the pinions 112, the corresponding total wheels are driven through the medium of the transmission 112 — bushings 113 — 114 — 115 — 119 — 30 (and others). The re-setting operation of the total wheels is executed while the pinions 112 are still out of mesh with the wheels 81.

The whole of the carry-over mechanism is simultaneously restored to its initial position as previously stated.

The three types of operation already mentioned above will now be discussed in succession.

The first of these consists of registering upon the slip-strip and the checking-strip a number (e. g. a reference) which is not to be taken into account.

Operation then is as follows: The number key 58 is first depressed. Such depression has the effect of causing the lever 78 to oscillate about

the shaft 55, this first causing the gears 79 to be raised and then to be disengaged from the teeth of gears 81; under these conditions, the transmission from the partial item wheels and from the total wheels is broken. On the other hand the lever 78 being connected through the part 260 to the hub 259, the latter, acting on roller 257, causes rotation of the frame 251 about the shaft 244. The rollers 255 and 256 rigid with said frame are then brought to bear upon the latch member 233 which, compressing the spring-plate 237, moves down and latches the total wheels as illustrated in Fig. 4. It will be noted however on this figure that the rollers 255 and 256 are not shown and that only the rollers 247 and 248 are visible. Actually, the upper part of Fig. 4 corresponds to a different instance to be considered later, but the position of the part 233 is the same in both cases.

The number is then made up on the keyboard of the machine. This keyboard, in known fashion, brings into action the selector drums which determine the amplitude of subsequent rotation of the digit-carrier and reference-carrier drums 1 to 7.

The general control mechanism of the machine is set into motion by actuating the "register" control which may be a crank (if the machine is manually controlled) or a push-button starting the motor of the machine (if a motor is provided).

It is known that, normally, the two latching members 233 and 238 are maintained depressed simultaneously by the rollers 248 and 250. For, as will be shown later on, the printing wheels should only be released for a definite operation: rotation, or clearing the zeros of the partial item wheels.

However in the present instance involving the registering of a number, the total wheels alone remain latched permanently by the rollers 255 and 256 brought into position by the number key 58 which remains depressed until the end of the operation. On the other hand, and as will be seen, the rollers 248 — 250 carried by the shaft 244 are temporarily disengaged from their position in between the two latching members 233 and 238, this enabling only the member 238 to move up again under the action of the spring-plate 240 (the member 233 remaining depressed by the action of rollers 255 and 256).

I shall now refer, in the description of operation, to the timing diagram of Fig. 21. During the first five degrees of rotation of the camshaft 270 (which has the same angular speed as the cam-shaft 142), the partial item wheels are maintained blocked by the pressure that the rollers 248 and 250 exert on the parts 233 and 238. But after these five degrees have been exceeded, the cam 269 operates the lever 266 which, through its teeth 265, rotates the pinion 264 rigid with the shaft 244. This results in a rearward retraction of the rollers 248 and 250, a retraction which allows the part 238 to move up again and consequently allows rotation of the partial item wheels.

These wheels cause through the medium of pinions 51, 53, 39 and 61, rotation of the check-strip printing wheels. In this way and at this time, the digits of the amount made up on the tabulating keyboard are then presented towards the printing block, and at the elevation of the slip-strip and checking strip.

The partial item wheels remain in their unlatched condition up to about the 80th degree of rotation of the camshafts 270 and 142. At that

time, and owing to the cessation of the action of cam 269 upon lever 266, the rollers 248 and 250 will relatch the partial item wheels.

Meanwhile, and shortly after the 50th degree of rotation of the above-mentioned camshafts, the cam 193 (Fig. 19) engages by its roller 194 and then by its roller 195, the parts 195 and 197 of the lever 186, which is rotated (Fig. 19) clockwise and moves the inking cylinder 185 from its idle position (in which it is lodged against the inking pad 187), to a position underneath the printing wheels.

It will be noticed (Fig. 21) that, owing to the temporary unlatching of the partial item wheels, the zeros of the latter have been released and have moved up; but the latching of these wheels, which occurs towards the 80th degree of the rotation of camshafts 270 and 142, produces the lowering of those among the zeros in these wheels which then stood on a vertical diameter; this has the effect of protecting the character of the adjacent total wheels from direct contact with the inking cylinder 185.

Inking of the printing wheels goes on until after one quarter revolution of the above-mentioned camshafts has been completed. Then, towards the 110th degree of rotation of these shafts, cam 176 engages roller 177 carried by shaft 178 rigid with printing block frame 151 and initiates the upward movement of the latter. Printing of the characters carried by the partial item wheels and the check-strip printing wheels occurs at the moment where the selected teeth of these wheels arrive into contact with the slip-strip 154 and the check-strip 157 presented at the top of the printing block. Towards the 130th degree of rotation of the camshafts 270 and 142, the teeth 189 engage the pinion 190 and produce a cocking of the ejector, if the latter was not already cocked. Rotation of the pinion 190 continues approximately as far as the 155th degree.

Towards the 190th degree of rotation of the said camshafts, the levers 202 and 207 (Fig. 17) come into action as previously stated and cause a rotation of the pinions 198 and 199. This results in the slip-strip being fed forward by an amount equal to one line space, that is about 10 mm., for the addition key has remained in its idle position. The check strip is simultaneously moved by its roller 164 which is rigid with a pinion adapted to mesh with a gear sector integral with one of the levers 186 carrying the inking cylinder (see Fig. 15).

On the 210th degree of rotation of the above-stated camshafts, the cam 176 (Fig. 19) is made inoperative and the block 151 is restored to its initial position, the printing being completed. Moreover, during the gradual depression of block 151, the remaining levers involved are gradually restored to their initial positions by their return springs.

On the 270th degree of rotation, the partial item wheels are again unlatched, until substantially the end of the revolution, to allow their being reset under the action of the digit-carrying cylinders. Toward the 335th degree of rotation, the number key 58 is returned to its position by the part 263 the roller 262 of which, acting on the sides of the notch 261 in part 18, restores said key to its initial position. Furthermore, by the action of hub 259, the rollers 255 and 256 are moved away from part 233. This part is then latched as at the start by the rollers 248 and 250 which the sector 265 has

restored in position owing to the action of cam 269 on lever 266.

I shall now consider the instance involving the second operation which consists of registering and recording a partial item or "sub-total."

If the machine includes a special "salesman" or "specialized account" key associated for instance with counters for registering the sum total of the sales made by the salesmen, this key is first depressed, then the partial item to be recorded is made up, by operating the appropriate keys on the machine's keyboard. The tabulating and analysing and composing mechanism operates as in the foregoing instance, then, by means of a suitable device, the general control mechanism of the machine is started. Nearly at the start of the rotation of the camshafts 270 (Fig. 20) and 142 (Fig. 19), the cam 268 acts on the lever 266 to rotate the shaft 244 which moves the rollers 248 and 250 away from the two latching members 233 and 238. All the printing wheels are thus unlatched. Rotation of the digit-carrying and marker-carrying cylinders 1 to 7 occurs and brings about the rotation of the partial item wheels for a time corresponding to the angle of rotation of the camshafts, a trifle less than 90°. In rotating the partial item wheels drive, through the gears 51, the elements of the shaft assembly 54 rigid with the gears 53. As the number key 58 is not depressed, the wheels 79 are in mesh with the gears 81, and these actuate the carry-over mechanism, as stated above in connection with a specific example; the carry-over mechanism rotates the total wheels through the medium of the gears 119 and the assembly 41.

Shortly before the end of one quarter of a revolution of the previously-mentioned camshafts, the partial item wheels are again locked and will so remain until the re-set operation which terminates the full partial item registering operation. The total wheels remain unlatched until about the 270th degree of rotation of the camshafts, and the total wheels can move to complete the carry-over operation (see description of this operation above). Latching of the partial item wheels, occurring toward the 90th degree of rotation of the camshafts, is accomplished by the rollers 248 and 250 restored temporarily to their positions by the cam 269. Printing, preceded by a general inking step and accompanied by the cocking of the ejection device, is followed by a feed of the check strip and the slip-strip by the amount of one line space, as in the foregoing case, since the addition key still remains undepressed. From the 270th degree of rotation of the camshafts, the partial item wheels are again unlatched by the rollers 248 and 250, owing to a fresh action of the cam 269. However, the total wheels are locked by the rollers 248 and 250 brought by the cam 269 against the edge 235 of part 233. Resetting of the partial item wheels occurs as in the foregoing case and is practically completed by the end of the camshafts' revolution; said camshafts however, act (cam 269) to ensure the simultaneous locking of the parts 233 and 238, as shown in Fig. 4.

I shall lastly discuss the third type of operation that may be involved in the printing of a total. This case is encountered when, after having registered in the way just described, several partial items, it is desired to obtain the total of these items. This totalizing operation is obtained without tabulation and without the action of the

analyzing and composing drums. It is brought about by the operation of any appropriate mechanism forming no part of the present invention adapted to start the general drive mechanism. Throughout the rotation of the camshafts 270 and 142, the partial item wheels, preliminarily reset to zero as shown in the foregoing operation, remain latched, except during a small interval of about 45°. This temporary unlatching has the purpose of relieving the pressure exerted by the latches 234 on the rings 44 of the partial item wheels (see Fig. 4). With this pressure relieved, the springs 50, acting on the tongues 46, cause said rings 44 to move up again and consequently the zeros of the partial item wheels to be retracted, such retraction clearing the useful teeth of the total wheels.

The first step in a "total" registering movement is the general inking step which occurs at the same instant and in the same way as in the foregoing cases. Printing is similarly accomplished, except that the ejector-cocking mechanism does not operate.

Towards the 110th degree of rotation of the camshafts, lever 213 brought to operating position by the action of part 216 on roller 214 of lever 213 (this part 216 having been moved from its position 217 to its full line position in Fig. 16 through actuation of the totalizing mechanism) causes upward motion of lever 220 which applies the slip-strip against the inking pad 225 and thus causes printing of the name of the firm, the date of the transaction, and, if desired, a number assigned to the latter.

Simultaneously, the cutter 222 engages into the slot 232 of part 231 and the slip is severed. The slip-cutting step stops towards the 135th degree of rotation of the camshafts, while the date- and name-printing operations terminate towards the 155th degree. The total print-taking step occurs at this time, advantage being taken of the retraction of the zeros on the partial item wheels, effective from about the 150th to the 190th degree.

Towards the 165th degree, the slip-ejecting mechanism, cocked at the last partial item operation, is started owing to the action of the part 226 of lever 213 on part 227 rigid with pawl 228 which releases gear 230 and thus allows the ticket to be ejected.

Feed of the slip-strip and of the check-strip are provided for as before, but with this difference however that owing to the actuation of the addition key, the roller 209 of lever 207 instead of cooperating with the narrow end 210 of part 217, now cooperates instead with the wider mouth opening 211 of said part. This results in the slip-strip being fed five line spaces rather than one.

Whereas the partial item wheels are blocked throughout the remainder of the rotation, the total wheels are released for a time corresponding to a rotation of about 45° of the camshafts to allow said wheels to be re-set.

Besides, the latching of the printing wheels is not brought about in the above-indicated way. For the cam 269, carried by shaft 270, is rigid with the tabulating mechanism and, since the latter does not come into action for a "total" operation, the rollers 248 and 250 are not actuated at the start of the movement.

For retraction of the zeros on the partial item wheels, indicated above, the said wheels are unlatched by a rotation of shaft 244 in a direction reverse from its normal sense of rotation, that is clockwise according to Fig. 20.

This reverse rotation has the effect of displac-

ing the rollers 248 and 250, causing them to leave the part 238 to bring them exclusively against the part 233; thus, the partial item wheels are unlatched while the "total" wheels remain locked.

6 This rotation in reverse sense of the shaft 244 is brought about by a special control (not shown in the drawing) and which in practice may include a cam mounted on an extension of the shaft 244 towards the left of Fig. 20.

10 To re-set the total wheels, the cam 144 of shaft 142 engaged by actuation of the totalizing mechanism, acts upon roller 145 of lever 146 which through its teeth 148 drives the sector 150 whose teeth 149 cause rotation of lever 132 which, as shown in connection with the carry-over mechanism's operation, accomplishes re-setting.

For such re-setting, the unlatching of the total wheels is produced by the ramp 271 and boss 272 of lever 132. Pawl 273 acts on lever 277 the nose

20 279 of which upon engaging the tenon 280, pushes back the lever 281, causing the shaft 244 to rotate counterclockwise and thus causes the rollers 248 and 250 to disengage the bead 235 to exert pressure only on the bead 239 of part 238. Thus, the

25 partial item wheels effectively remain locked, but the total wheels are unlocked, and this allows them to be re-set (which occurs between a point a little beyond the 270th degree and the 320th degree of the camshafts' rotation). At the end of the stroke, i. e. towards the 320th degree, the projection 271 acts on the pawl 273 which unlatches roller 275 and stirrup 274. Consequently

30 the lever 281 is released and restored to idle position, in which the rollers 248 and 250 act simultaneously on the parts 233 and 238.

35 It will be observed, upon examination of the various parts of the device illustrated in the accompanying drawings, that such parts may be made from stampings or assemblies of stampings.

40 Parts having a very peculiar contour and shape are quite the exception, so that the device may be constructed in a simple and economical manner, and this represents a yet further advantage of this device over those of similar type designed to this day, and which, in addition to their intricate and expensive construction, possess drawbacks due to the fact that a great number of mechanisms, each highly complex and frequently ill adapted to the others, are grouped within a restricted space.

45 Naturally the form of embodiment which has been described by way of example is not the only form under which the device according to the invention may be constructed, and, it is to be understood that modifications may be made therein without altering the general features of the invention.

50 What I claim is:

55 1. In a selective multiple printing register for calculating machines and the like, first and second character printing wheels, said wheels being adjacent and rotatable about a common axis, each numeral wheel having its periphery divided into a plurality of sectors, each sector having a printing character formed on its periphery, except that said first wheel has a recess at one of its sectors, said second printing wheel having a radius smaller than that of said first printing wheel but substantially larger than the radius of the bottom of said recess, a printing member having a portion received in the recess of the first wheel and bearing a printing character on its periphery, means connecting said member to the first wheel for concurrent rotation therewith

60 70 75 and for limited radial movement with respect

thereto between a retracted position wherein said printing character is within the radius of said second printing wheel and a printing position wherein said printing character is radially aligned with the periphery of said first printing wheel, spring means biasing said member to its retracted position, means for producing relative radial movement between said printing wheels and a sheet to be printed in a sense to impress the peripheries of said wheels against said sheet, said first wheel being then effective due to its larger diameter to impress one of its characters on said sheet unless said item wheel is in a neutral position wherein the character on said printing member is nearest said sheet, and means for moving said printing member to its printing position against said spring means, said printing member moving means being effective when said first wheel is in its neutral position to determine whether a character on said second wheel or the character on said member is printed on said sheet.

2. In an item and total printing register for calculating machines and the like, a settable item printing numeral wheel, a total printing numeral wheel adjacent said item printing wheel, said wheels being rotatable about a common axis, each numeral wheel having its periphery divided into ten equal sectors, the total printing numeral wheel having printing numerals from 0 to 9 formed on its respective sectors, the item printing numeral wheel having printing numerals from 1 to 9 formed on nine of its sectors and a recess at the tenth sector, said total printing numeral wheel having a radius smaller than that of said item printing wheel but substantially larger than the radius of the bottom of said recess, a zero printing member having a portion received in the recess of the item wheel and bearing the printing numeral 0 on its periphery, means connecting said member to the item wheel for concurrent rotation therewith and for limited radial movement with respect thereto between a retracted position wherein said numeral 0 is within the radius of said total printing wheel and a printing position wherein said numeral 0 is radially aligned with the periphery of said item printing wheel, spring means biasing said member to its retracted position, means for producing relative radial movement between said numeral wheels and a sheet to be printed in a sense to impress the peripheries of said wheels against said sheet, said item wheel being then effective due to its larger diameter to impress one of its numerals on said sheet unless said item wheel is in a zero angular position wherein said zero printing member is nearest said sheet, and means for moving said zero printing member to its printing position against said spring means, said zero printing member moving means being effective when said item wheel is in its zero angular position to determine whether a numeral on said total wheel or the zero on said member is printed on said sheet.

3. In an item and total printing register for calculating machines and the like, a settable item printing numeral wheel, a total printing numeral wheel adjacent said item printing wheel, said wheels being rotatable about a common axis, each numeral wheel having its periphery divided into ten equal sectors, the total printing numeral wheel having printing numerals from 0 to 9 formed on its respective sectors, the item printing numeral wheel having printing numerals from 1 to 9 formed on nine of its sectors and a recess at the tenth sector, said total printing numeral wheel

having a radius smaller than that of said item printing wheel but substantially larger than the radius of the bottom of said recess, a zero printing member having a portion received in the recess of the item wheel and bearing the printing numeral 0 on its periphery, means connecting said member to the item wheel for concurrent rotation therewith and for limited radial movement with respect thereto between a retracted position wherein said numeral 0 is within the radius of said total printing wheel and a printing position wherein said numeral 0 is radially aligned with the periphery of said item printing wheel, spring means biasing said member to its retracted position, means for producing relative radial movement between said numeral wheels and a sheet to be printed in a sense to impress the peripheries of said wheels against said sheet, said item wheel being then effective due to its larger diameter to impress one of its numerals on said sheet unless said item wheel is in a zero angular position wherein said numeral 0 is nearest said sheet, means for moving said zero printing member to its printing position against said spring means, said zero printing member moving means being effective when said item wheel is in its zero angular position to determine whether a numeral on said total wheel or the zero on said member is printed on said sheet, means for setting items on said item wheel and resetting said item wheel to said zero position, means for transferring each setting of said item wheel to said total printing wheel, means for operating said radial movement producing means and said zero printing member moving means while an item is set on said item wheel to print said item on said sheet, and means for operating said radial movement producing means and keeping said zero printing member moving means inactive while said item wheel is reset to its zero position to print the total on said sheet.

4. In an item and total printing register for calculating machines and the like, a plurality of settable item printing numeral wheels corresponding to a plurality of denominational orders, a like plurality of total printing numeral wheels, each respectively adjacent its corresponding item printing wheel, said wheels being rotatable about a common axis, each numeral wheel having its periphery divided into ten equal sectors, the total printing numeral wheels having printing numerals from 0 to 9 formed on their respective sectors, the item printing numeral wheels having printing numerals from 1 to 9 formed on nine of its sectors and a recess at the tenth sector, said total printing numeral wheels having a radius smaller than that of said item printing wheels but substantially larger than the radius of the bottoms of said recesses, a like plurality of zero printing members, each having a portion received in the recess of one of the item wheels and bearing the printing numeral 0 on its periphery, means connecting said member to the adjacent item wheel for concurrent rotation therewith and for limited radial movement with respect thereto between a retracted position wherein said numeral 0 is within the radius of said total printing wheels and a printing position wherein said numeral 0 is radially aligned with the periphery of said item printing wheel, spring means biasing said member to its retracted position, means for producing relative radial movement between said numeral wheels and a sheet to be printed in a sense to impress the peripheries of said wheels against said sheet, each said item wheel being

then effective due to its larger diameter to impress one of its numerals on said sheet unless said item wheel is in a zero angular position wherein said numeral 0 is nearest said sheet, means for moving said zero printing members to their printing positions against said spring means, said zero printing member moving means being effective when said item wheels are in their zero angular positions to determine whether numerals on said total wheels or the zeroes on said members are printed on said sheet, means for setting items on said item wheels and resetting said item wheels to said zero position, means for transferring each setting of said item wheels to said total printing wheels, means for operating said radial movement producing means and said zero printing member moving means while an item is set on said item wheels to print said item on said sheet, and means for operating said radial movement producing means and keeping said zero printing member moving means inactive while said item wheels are reset in their zero positions to print the total on said sheet.

5. In an item and total printing register for calculating machines and the like, a plurality of settable item printing numeral wheels corresponding to a plurality of denominational orders, a corresponding number of concentric independently rotatable hollow shafts, each having at least one end projecting beyond the end of the next larger shaft, each said numeral wheel being fixed on the projecting end of one shaft, a plurality of total printing numeral wheels, each rotatably mounted on the projecting end of one shaft, each numeral wheel having its periphery divided into ten equal sectors, each total printing numeral wheel having printing numerals from 0 to 9 formed on its respective sectors, each item printing numeral wheel having printing numerals from 1 to 9 formed on nine of its sectors and a recess at the tenth sector, said total printing numeral wheels having a radius smaller than that of said item printing wheel but substantially larger than the radius of the bottoms of said recesses, a plurality of zero printing rings, one ring encircling said shaft adjacent each said item printing numeral wheel, each ring having a

peripheral projection bearing the printing numeral 0 and offset so as to be received in the recess of the adjacent item wheel, said ring having an elongated central aperture to receive the hollow shaft and permit radial movement of the projection in the recess between a retracted position and a printing position wherein said 0 numeral is radially aligned with the other numerals on the item wheel, means connecting each said ring to its associated item wheel for concurrent rotation therewith, spring means biasing said ring to its retracted position, means for bringing a surface to be printed into engagement with axially aligned printing numerals on said wheels to print said numerals on said surface, means effective during an item printing operation to move to their printing positions any 0 numerals which may be adjacent said surface, and means including said spring means and effective during a total printing operation to move all said 0 item numerals to their retracted positions so that only the numerals on the total printing wheels are printed on said surface.

6. An item and total printing register for calculating machines and the like as defined in claim 2, including means for locking said item wheel against rotation, separate means for locking said total wheel against rotation, and means for selectively operating either of said locking means alone or both simultaneously.

ROBERT LÉON GOURDON.
